UNITED STATES PATENT OFFICE.

HUGO F. SCHROEDER, OF TORRINGTON, CONNECTICUT, ASSIGNOR TO SCHROEDER BROTHERS MANUFACTURING COMPANY, OF TORRINGTON, CONNECTICUT, A COPARTNERSHIP CONSISTING OF HUGO F. SCHROEDER, ERNEST E. SCHROEDER, RICHARD F. W. SCHROEDER, GUSTAVE A. SCHROEDER, JR., AND ARTHUR E. R. SCHROEDER.

METHOD OF MAKING NUTS AND ARTICLE MADE THEREBY.

Application filed June 29, 1921. Serial No. 481,200.

To all whom it may concern:

Be it known that Hugo F. SCHROEDER, a citizen of the United States, residing at Torrington, in the county of Litchfield and 5 State of Connecticut, has invented certain new and useful Improvements in Methods of Making Nuts and Article Made Thereby, of which the following is a specification.

This invention relates to a method of making nuts and to the article made thereby. According to the method I can produce in 10 a very simple and satisfactory manner a highly efficient nut which will properly resist any strains to which it may be subjected in practice and which will be held in a 15 certain manner against rotation.

In the drawings accompanying and forming part of the present specification, I have shown in detail one of the several forms of 20 carrying the method into effect and in said drawings there is also illustrated a form of embodiment of the resultant article. Obviously I am in no sense restricted to such disclosure. I may depart therefrom in several 25 respects within the scope of the invention defined by the claims following said description.

Referring to said drawings:

Figure 1 is a front elevation of a blank 30 partially formed.

Fig. 2 is a view as seen from the right end in Fig. 1.

Fig. 3 is an enlarged sectional detail.

Fig. 4 is a side elevation of the partly 35 formed-up blank.

Fig. 5 is an end elevation of the same as seen for instance from the right in Fig. 4.

Fig. 6 is a side view of the finished article and

Fig. 7 is an end view as seen for instance from the right in Fig. 6.

Like characters refer to like parts throughout the several views.

A nut involving the invention, can be employed with advantage in any of the connections where those of the ordinary kind are usable, although the same is of particular advantage when employed as part of the equipment of a tool such as a hack saw it 45 being situated in this particular instance, in the handle of the saw and being keyed to a wall of the socket in which it is fitted 50

and having for such purpose an external key or fin extending preferably throughout the entire length thereof or in the direction 55 of the longitudinal center whether the complete length or not.

Initially I take a piece of proper sheet stock such as 1 and usually of metal, rolling it spirally as at 2. When the sheet or 60 blank is thus rolled there will be formed upon opposite surfaces of it threads which may be pitched to the desired size. At the same time there is desirably rolled on the blank the outwardly-extending wings 3 and 65 4 which are desirably situated on the external side of the blank as shown in both Figs. 1 and 2. The first step therefore comprises with the aid of suitable dies or otherwise, the spiral rolling of the blank to produce threads on both sides of the blank and concurrently the formation of the wings 3 and 4 these wings when the nut is finished merely abutting, being not interlocked and presenting jointly the external key of the 75 nut.

Subsequent to the threading and the winging of the blank in the manner described, it is formed up into U-shape or practically so as shown in Figs. 4 and 5 by dies or otherwise. After the blank has been made into U-form practically as described, it is with the aid of a suitable mandrel or in some proper manner shaped into cylindrical form as illustrated for example in Figs. 6 and 7. 80 85

In shaping up the blank from the second to the third step, the side edges of the body 5 of the blank are brought together and merely abut as clearly shown in Fig. 7. At the same time the inside faces of the two 90 wings are brought together or into contact to make the key 6 which as shown extends throughout the complete length of the practically cylindrical nut externally thereof. The wings 3 and 4 merely abut and are not 95 interlocked so that when desired under certain circumstances the nut may expand yet it cannot contract beyond the limits permitted by the abutting of the wings 3 and 4 and the side edges of the blank. 100

It will be clear from the foregoing description that the nut is split, the split or edge portions thereof being in abutment and being provided with wings which solely abut

2
against each other on their inner sides to form a key external of the nut and desirably extending throughout the complete length thereof. Desirably the nut is made from 5 sheet metal stock.

What I claim is:

1. A method comprising rolling a thread in a sheet and forming on the sides of the sheet wings, and afterward forming the 10 rolled-winged-sheet into a cylinder with the edges of the sheet and the wings solely in abutment to form an externally-threaded nut.

2. A nut internally and externally threaded and split, the split portions being in abutment and being provided with wings which solely abut against each other on their inner sides to form a key longitudinally and externally of the nut. 15

3. A nut internally and externally threaded and split, the split portions being in abutment and being provided with wings which solely abut against each other on their inner sides to form a key longitudinally and externally of the nut, and extending throughout the complete length thereof. 20 25

4. A nut split throughout its length, the split portions being in abutment and being provided with wings which solely abut against each other on their inner sides to 30 form a key external of the nut longitudinally thereof.

In testimony whereof I affix my signature.

HUGO F. SCHROEDER.
